TRANSFORMABLE STAINLESS STEEL

Albert M. Hall, David C. Ludwigson, and Donald B. Roach, Columbus, and Virgil W. Whitmer, Canton, Ohio, assignors, by mesne assignments, to Republic Steel Corporation, Cleveland, Ohio, a corporation of New Jersey

No Drawing. Filed May 29, 1959, Ser. No. 816,681

6 Claims. (Cl. 75—125)

This invention relates to the manufacture of stainless steel and more particularly to improved stainless steel alloys and their treatment. An important aim of the invention is to provide superior mechanical properties, including exceptionally high strength as well as excellent hardness and other desirable characteristics in parts or articles ultimately fabricated from the alloys, a further aim being the attainment of these results while providing for production of the metal in a readily fabricable state prior to a convenient, final treatment which produces the special mechanical properties. A further advantage of the new alloys is that as ultimately fabricated they also have a high degree of corrosion resistance, which is, of course, a property of essential importance in stainless steels.

In essence, these aims are achieved by the provision of a novel alloy which will allow not only the original forming of the metal to a desired shape, e.g. as by rolling to strip, sheet or the like, but which will also provide the desired fabricability, conveniently after a final or so-called trigger anneal, to make various parts or articles, and which will thereafter be susceptible of a relatively simple treatment, that may specifically include a refrigeration step, to transform the fabricated structures or parts into a metallic state having the desired strength, hardness or the like.

Stated in another way, a primary purpose of the invention is to produce an alloy which in one condition is ductile or otherwise readily fabricable, preferably at room temperature, and which can easily be transformed to another condition where it has the special mechanical properties described above. More specifically, the invention provides an improved alloy of the type that is first austenitic and thus easily formable, and that is readily processed to final hardened form by transformation to martensite and subsequent aging or tempering. The ultimate, hardened article of the novel alloy has properties, e.g. of tensile strength or yield strength, substantially superior to those heretofore obtainable in stainless steels by any similarly expeditious treatment or without using components that are more costly or that may have undesirable effects in other ways. The new alloy is particularly advantageous in that it does not require a content of highly oxidizable elements such as aluminum or titanium.

The improved stainless steels of the invention attain the stated results by a novel combination of elements, including certain special components, new in use or proportion or both, coating with specific base components selected and proportioned to have desired fundamental

2

characteristics as described above. The improvement in properties of articles or parts made from the alloys appear to be obtained, at least in part, by the change or phenomenon that is commonly called precipitation hardening, and for commercial identification the compositions may therefore be referred to as new precipitation-hardening alloys. It should be understood, however, that the invention is not limited or affected by the scientific accuracy or inaccuracy of the term precipitation hardening or by any factual determination whether the enhancement of mechanical properties in the new alloys is or is not accomplished by the same physical or chemical mechanism as has previously been described by that term.

15 As explained, the new alloy is hardened by transformation to martensite, e.g. by refrigeration. For effective development of the improved properties, the martensitic transformation is followed by a heat treatment, e.g. at about 850° F., which may be called a 20 tempering or an aging treatment. Presumably this final operation brings about or completes the so-called precipitation hardening, and also tempers or strengthens the martensitic structure; but whatever the actual phenomena, the effect of this step is a marked enhancement of the 25 mechanical properties, and appears to result, at least in considerable part, from the new addition or additions in the alloy.

The new composition is, as stated, one which can be 30 conditioned so that it will transform to martensite at very low, e.g. sub-zero, temperature. Thus for initial forming, as in rolling to sheet, the alloy may be annealed at 1900° F. and as so annealed will be stable in the austenitic form; it is then given a special or trigger anneal at, say, 1700° F., whereupon it will still be austenitic down to room temperature, but is transformed to martensite on cooling to —30° to —100° F. It will be understood that if desired, other ways may be followed for effecting transformation of the metal to martensite or for conditioning the metal for such transformation, i.e. referring to the metal in its stable austenite form existing after anneal at 1900° F. One such method is so-called intergranular precipitation of carbon on holding the alloy at 1400° F., and another is cold working, which has obvious limitations in practice. 40 45 In most cases, the operations leading to and involving transformation by refrigeration are greatly preferred, as of special convenience (e.g. since final fabrication can be performed at room temperature after the trigger anneal) and as providing best realization of all improved properties.

One example of a base alloy susceptible of transformation to martensite by low temperature cooling has the following composition: 17% chromium, 4.5% nickel, 55 2% manganese, 0.12% carbon and 0.5% silicon, with the balance iron except for minor incidental impurities. This alloy, when annealed one or more times at 1900° F. (e.g. for rolling) is essentially stable austenite, but after a special or trigger anneal at 1700° F. becomes capable of low temperature transformation, while remaining austenitic at room temperature so as to permit ready fabrication of various articles, parts or structures. Such metal may thereafter be subjected to refrigeration, say at —100° F. for a suitable length of time, such as eight hours, followed by a moderate heating, specifically a

tempering treatment at about 850° F. for one hour or so. The low temperature treatment is effective to transform the structure to virtually 100% martensite, with some increase in the strength and ductility of the martensitic structure by the subsequent tempering operation.

As indicated, the present invention embraces the discovery that in stainless steel alloys of the above character, markedly improved mechanical properties of the ultimate product (i.e. after the described treatments) are achieved by certain new additions to the composition, which at the same time are such as to avoid some difficulties or disadvantages that have attended prior proposals for improving this type of alloy. The elements constituting the new additions, in special proportions or relationships as described below, are boron, copper and phosphorus.

Reference is first made to boron, which has not heretofore been used or proposed for precipitation-hardening or like purposes; when included in amounts ranging from 0.02% to 0.7% of the alloy (all percentages herein being given by weight), it contributes significantly to the mechanical properties, especially in promoting or effectuating the final hardening of the metal. Especially good results have been achieved by the inclusion of both boron and copper, the former in a range upwards of 0.01% and the latter very preferably within an economically advantageous range of about 0.75% to 1.75%; the alloy containing both of these elements is regarded as a specific and particularly important aspect of the invention, affording markedly superior properties.

While copper in larger amounts, usually upward of 3%, or at least in amount of 2% or more, has been used or proposed for some strengthening effect in certain prior stainless steel alloys, it now appears that the described conjoint inclusion of both boron and copper in the present compositions, affords improvement significantly greater than is obtainable with either element alone, or with larger quantities of either element. In combination with one or both of the other new additions, however, copper can be included, if desired, in somewhat larger quantities than the range mentioned above, the greater range being 0.5% to 3.0%. For instance, when copper is so included along with boron, a considerable measure of the advantage which attends the specific combination of these elements described above, is realized, but unusual practical advantage appears to accrue by keeping the copper content of the combination within the new, low range. Indeed, the addition of copper alone, in this special range (e.g. up to 1.75%), has a definite value for the strength of the ultimate product, a result not heretofore appreciated or recognized with respect to the base alloys of the specific refrigeration-hardenable type here contemplated.

A third element of the described group of new additions is phosphorus, incorporated in the alloy in amounts ranging from 0.08% to 0.40%; in such quantities, phosphorus also materially improves the metal, apparently in contributing characteristics of so-called precipitation hardening. Indeed although phosphorus, generally in larger amounts, has been employed for some beneficial effect in other types of stainless steels, notably those characterized only by, or designed to remain in, an austenitic condition, it does not appear to have been heretofore known or apparent that phosphorus would or could be effective for precipitation hardening from martensite. Phosphorus may be used very effectively in combination with one or both of the other additions, for example in an alloy which also contains boron and copper, such as with the presently preferred proportions of boron, 0.1% to 0.3%, and copper, 0.75% to 1.5%. The content of phosphorus which is now preferred in combination with one or both of the other elements herein contemplated for effectiveness in hardening the martensitic form of the metal, is from 0.1% to 0.3%. As stated, however, the invention contemplates alloys

in which phosphorus alone, from the described group, is employed for its newly discovered effect, i.e. up to 0.4%.

In presently preferred form, the alloy also includes 5 molybdenum, as in amount ranging up to 4%, or preferably from 1.5% to 3.5%, with special benefit to the final, hardened products, notably in improving the strength of the material at elevated temperatures. Additional or alternative components are metals of the class 10 consisting of tungsten and vanadium; although present evidence is that molybdenum is considerably more effective for such purposes, these other additions appear useful for enhancing some properties, viz. tungsten for high 15 temperature strength and vanadium for improving the adaptability of the metal to drawing at higher temperatures, i.e. prior to transformation and hardening.

A composition of specifically superior properties, to 20 which the invention in a correspondingly specific sense is directed, is an alloy of the described base type containing boron from 0.01% to 0.3%, copper from 0.75% to 1.75% and molybdenum from 0.15 to 3.5% especially preferred results being obtainable with boron in the more limited range of 0.04% to 0.2% and molybdenum between 2% and 3%.

25 As stated above, it appears that each and all of the new additions, viz. boron, copper and phosphorus in the proportions and relationships indicated, exert their improved effects primarily in connection with the final treatment, i.e. in the final aging or tempering after transformation to martensite has been effected. It is also 30 of special significance that all of these and other additions (notably molybdenum) described above have no deleterious effect on other characteristics of the metal, and in particular do not adversely affect the readily 35 fabricable character of the alloy in its annealed austenitic conditions, i.e. either after the working anneal at 1900° F. or the trigger anneal at 1700° F.

The special nature of the base alloy is critical for the 40 ultimate results described, including the novel effects of the additions. Thus one important feature of the alloy of the invention is its essentially stable austenitic character after annealing at 1900° F., whereby it can be rolled or otherwise worked with relative ease and whereby it does not transform to martensite, even at temperatures 45 far below freezing. A second important feature is the adaptability of the base alloy to assume less stable austenitic properties, for example the conversion effected by trigger anneal at 1700° F., whereby the metal remains austenitic and fabricable even at room temperature, yet 50 it is easily and substantially transformed to martensite by refrigeration. After the transformation, the desired characteristics are further enhanced by the moderate heat treatment, i.e. so-called tempering. This combination 55 of properties is achieved by appropriate balance, in the base alloy, of those elements which tend to stabilize ferrite (mainly chromium and silicon) and those elements which tend to stabilize austenite (e.g. carbon, nickel and manganese). Silicon is not essential of itself, but as a rule is unavoidably present and must therefore be taken 60 into account in balancing the components of the alloy, as will be understood by those familiar with compositions of this type.

Furthermore, in processing, the extent of carbon taken 65 into and remaining in solution is important, e.g. in that for refrigeration hardening there must be some carbon so remaining after the trigger anneal. For example, in one prior type of stainless steel alloy, there have been included elements such as titanium and columbium which tend to form carbides, substantially more strongly than chromium. Thus when such alloy, containing say up to 0.1% or 70 0.12% carbon, is annealed, for example at 1900° F., the strong carbide formers combine with the carbon, removing all but a very small amount (e.g. 0.02%) of the carbon from solid solution. It is understood that chromium itself does not remove carbon from solid solution

at 1900° F. but as stated, the stronger carbide formers do so. In consequence, the alloy containing them, while austenitic at the annealing temperature, is largely depleted of carbon and therefore transforms or tends to transform to martensite upon cooling to room temperature. Martensitic material, of course, is not readily fabricable.

In the base alloys to which the present invention is directed, the response to annealing treatments is considerably different. If annealed at about 1900° F., these alloys, containing say 0.12% carbon, will thereafter retain all of such carbon in solid solution. With such carbon content, the structure is still austenitic upon cooling to room temperature or even below. Conversion to martensite of the material in such state is not readily attainable. If, however, the alloy is alternatively, or thereafter, annealed at about 1700° F., it appears that some of the carbon is precipitated as chromium carbide, for example about 0.05%, while the remainder, about 0.07%, stays in solid solution. It further appears that this reduction of the amount of carbon in solution adjusts the transformation characteristics of the austenite so that it will transform to martensite when cooled to a readily attainable point below room temperature, e.g. in the range of -30° F. to -100° F. At the same time, the material is sufficiently austenitic, following the trigger anneal at 1700° F., to be readily fabricated at room temperature, as by many types of operation such as cutting, punching, bending, pressing, drawing, stamping and machining; austenitic structures have desirable forming characteristics, being relatively soft and ductile. Hence an important attribute of the selection and proportion of the alloy components is that some of the carbon will remain in solution after the trigger anneal, whereby the stability of austenite is modified no further than is necessary to provide martensite transformation at a convenient, sub-zero temperature.

It may also be noted that some variation in the content of carbon in solution after the final anneal can be availed of to adjust the processing and ultimate characteristics of the alloy. That is to say, increasing the dissolved carbon content lowers the temperature of martensite formation, but also increases the strength of the martensite formed.

Moreover, the alloy is such, as previously explained, that transformation to martensite can be reached in other ways. For instance, if it is finally annealed at 1400° F. instead of 1700° F., the stability of austenite is more considerably reduced (presumably by greater removal of carbon from solution), so that the metal will become martensitic when or even before room temperature is reached. Alternatively, cold working, if suitably uniform, can have a like effect, indeed of immediately causing transformation to martensite.

A considerable number of tests have demonstrated the new results of the alloys of the invention; representative groups of such tests are reported below, such reports also serving to provide description of suitable examples of the new compositions.

In one set of tests a series of alloys were prepared, in all cases including a base composition of 17% chromium, 4.5% nickel, 2.0% manganese, 0.12% carbon and 0.50% silicon, with the balance iron (and incidental impurities) except for additions in accordance with the invention as stated below. This base is identified in Table I below as Base No. 1. Some alloys were also prepared with the same base composition except that manganese was present in amount of 2.5% instead of 2.0%, these alloys being described as including Base No. 2. As will be seen from the table, the alloys specifically prepared included Base No. 1 without additions, and various compositions of the invention, consisting of Bases No. 1 and No. 2 respectively with further elements. In each case, a test ingot of the specific alloy was cast, and appropriate specimens of size and shape to suit the standard requirements for the several tests were prepared. The operation on each test specimen included annealing the specimen at 1700° F.

for one-half hour, and then after cooling to room temperature, subjecting the specimen to refrigeration at -100° F. for eight hours. After this chilling or freezing treatment, the specimen was allowed to resume room temperature and was thereafter treated by heating to 850° F. for one hour. All tests in the table were made with specimens which had been subjected to this series of operations.

The properties tested were hardness, yield strength, tensile strength and elongation, the results for the various alloys being as follows:

TABLE I

15	Alloy	Rockwell "A" Hardness	0.2% Offset Yield Strength, 1,000 p.s.i.	Tensile Strength, 1,000 p.s.i.	Elongation, Percent in.	
					1"	2"
20	Base No. 1	72	187	212	14.5	10
	Base No. 1+0.30% B	73.5	200	218	8	4.5
	Base No. 1+1.5% Cu	73.5	201	222	14.5	8.5
	Base No. 1+0.15% P	74.5	209	237	9.5	8
	Base No. 1+1.0% Cu +0.15% P	74.5	207	232	11.5	9.5
	Base No. 1+1.0% Cu +0.30% B	75	222	240	8.5	5.5
	Base No. 1+1.5% Cu +0.20% P+0.30% B	75.5	231	246	6.5	5
	Base No. 1+0.15% P +0.30% B	74.5	212	237	10.5	8
	Base No. 2+0.30% B	74	217	236	9.5	7.5
	Base No. 2+0.5% Cu	73.5	202	224	17.5	13
30	Base No. 2+0.15% P	73.5	194	223	19	15

It will be seen that all of the alloys containing the new additions or combinations of them showed marked improvement of physical properties, particularly hardness (over 73), yield strength (improved by 5%-20%) and tensile strength (increased, from several percent to 15%), as distinguished from the base alloy, exemplified by base alloy No. 1. Tests of all the characteristics were also made of specimens of each of the above tabulated alloys, where the test pieces were simply annealed to 1700° F. for one-half hour and then cooled to room temperature, without the subsequent treatments of freezing and heating. In such cases, the Rockwell "A" hardness ranged from 54.5 to 62, the offset yield strength from 42,000 to 57,000 p.s.i. and the tensile strength from 158,000 to 192,000 p.s.i., with elongations in both one inch and two inches ranging from about 13% to about 25%. In general, the variations among the alloys in the trigger-annealed but otherwise untreated condition seem to bear no special relation to the alloying additions. In all cases such properties were representative of the austenitic condition and indicated ready adaptability of the metal to fabrication or working as desired. Thus the tests indicated that all of the alloys have the advantageous austenitic character in their annealed condition, yet after the further transformation and hardening treatment, showed unusually high strength and hardness, which was of substantially improved nature in the new or special alloys.

These and other investigations have also demonstrated that in the special case of compositions containing both boron and copper, i.e. in amounts respectively ranging upward from 0.01% and 0.5% and within the upper limits indicated hereinabove, exceptionally good mechanical properties are achieved. Although the various additions did not in general reveal any deleterious effect on the base alloy in its annealed condition, i.e. relative to fabricability, there was some indication that boron alone tended to reduce ductility to some extent, whereas if boron and copper were included together, such reduction of ductility (relative to the base alloy) was not apparent.

The following table shows high temperature test results of a number of further examples of alloys, containing the copper-boron addition, and also other components, viz. molybdenum as now preferred for high tem-

perature properties, or alternatively tungsten, or both molybdenum and vanadium:

TABLE II

Alloy Number	Composition										Tensile Strength at 800° F., 1,000 p.s.i.
	C	Mn	Si	Ni	Cr	Cu	B	Mo	W	V	
398.....	0.12	2.5	0.50	4.5	16.5	1.0	0.20	1.0	-----	-----	176
400.....	0.12	2.5	0.50	4.5	16.0	1.0	0.20	1.5	-----	-----	198

420.....	0.125	2.03	0.44	4.35	16.50	0.92	0.10	2.30	-----	0.38	182

Alloys containing one or more of the ingredients molybdenum, tungsten and vanadium appear to have unusual practical value, the inclusion of molybdenum being of special significance in making a composition which is exceptionally useful for the purposes here contemplated.

While it will be understood that in general the desired mechanical properties of the alloys are determined by the selection and mutual proportions of the various components and by appropriate balance of their effects, as is indicated above and in some respects more fully below, and likewise that the total of alloying ingredients or of a major group of them is not alone a determinant of superior properties, it may be mentioned that preferred examples of the composition have usually contained from about 23.5% to about 29.5% of elements other than iron, and mostly from about 25% to about 28% of such elements. Like experience is that the total of elements selected from the group of chromium, molybdenum, silicon, nickel and manganese has been from about 22.5% to about 25.5% in the preferred alloys, and more specifically about 24% to about 25.5% in the best examples tested.

As indicated, although at present there is reason to describe the additions of boron, copper and phosphorus as functioning by causing so-called precipitation-hardening, it is possible that these elements act in some other way, either wholly or in part, to improve the transformation properties, e.g. in the general course of conversion to martensite by refrigeration and in further change during the subsequent heat treatment. It seems clear, however, that these elements do not function as carbide formers; indeed, on the contrary, they do not interfere with the desired maintenance of a significant proportion of the carbon in solution following certain annealing stages, so as to keep the metal substantially as austenite at room temperature.

Some variation in the proportions of ingredients may be made, within the requirement that the base alloy involve appropriate balance of elements stabilizing ferrite and elements stabilizing austenite, i.e. balance of such elements to achieve the desired austenitic character of the annealed metal and subsequent hardening by transformation, in a manner which will now be readily understood. Thus in its broadest ranges the base alloy composition (all proportions here, as elsewhere, by weight) may consist essentially of 12% to 20% chromium, 1% to 7% nickel, 0.5% to 5% manganese, 0% to 1% silicon and 0.06% to 0.2% carbon, the balance in all cases, except for the special additions and except for incidental impurities to be expected in these alloys, being iron. A further critical limitation, however, is that the total content of nickel and manganese (which tend to stabilize austenite) be no higher than 7.5%, i.e. in order to assure the desired capability of transformation. The alloy can be defined as including (with the above components) the special additions as: 0% to 0.7% boron, 0% to 3.0% copper, and 0% to 0.4% phosphorus, at least one of these elements being present in amounts of: at least 0.04% boron, 0.75% to 1.75% copper, and at least

0.08% phosphorus. It is noted that the stated minimum amount of phosphorus (i.e. minimum for effectiveness)

is significantly greater than quantities of this element which may be adventitiously present. Useful effect of boron, moreover, in promoting precipitation-hardening or the like, has been noted for amounts of this element down to 0.01%, quantities of 0.02% or more being somewhat preferred. In addition, the alloy may embrace, and its description therefore includes: 0% to 4% molybdenum, 0% to 4% tungsten and 0% to 1% vanadium. Among incidental impurities mentioned above, there may be, for instance, sulfur up to a maximum of 0.04%.

In a specific sense the advantages of the invention are realized in a definitely superior way, by base alloys where the above-named ingredients for such alloy are present in about the following proportions (now greatly preferred): 14.5% to 17.5% chromium, 3% to 5.5% nickel, 2% to 4% manganese, 0.3% to 0.7% silicon and 0.10% to 0.14% carbon, it being understood that the same upper limit for total nickel and manganese prevails, and that silicon may be omitted but is almost invariably present, to at least the stated minimum, as a necessary consequence of alloying and melting procedures. Other components of the preferred alloys are 1.5% to 3.5% molybdenum, 0% to 1.5% tungsten and 0% to 0.4% vanadium. The addition of the new components can be included as indicated above, a preferred maximum for phosphorus being 0.3%, and a preferred range for boron being 0.04% to 0.30% (with special preference for some purposes at 0.10% and above) and for copper 0.75% to 1.5%. The balance of the alloy is, as previously stated, iron, except for minor incidentals.

It will be readily understood that the components of the base alloy can be mutually proportioned, under principles known in the art, for provision of optimum balance between elements tending to produce austenite and elements tending to produce ferrite at elevated temperatures, and also for such total of the basic alloying ingredients as will afford the optimum desired character of austenite stability. Account is preferably taken, in such balancing, of additional components of the nature of molybdenum and the like; thus when molybdenum is included, less chromium may be used. For example, the chromium content can be reduced, from 17% or thereabouts, by 0.7% (percentage as based on the total alloy) for every 1% of molybdenum added; on the other hand it may sometimes be desirable to keep a relatively high level of chromium when molybdenum is present (Table III below), e.g. thus permitting a small sacrifice of mechanical properties in favor of retaining the highest corrosion resistance.

Another and particularly useful example of a specific composition of the alloy, expressed as a close range of percentages for each element or an approximate percentage (to account for tolerance in commercial production) is: 15% to 17% chromium, 4% to 6% nickel, 2% to 2.5% manganese, 0.3% to 1% silicon, 0.10% to 0.15% carbon, 0.5% to 1.0% copper, 0.10% to 0.20% boron, 2% to 3% molybdenum and 0.10% to 0.38% vanadium, with the balance iron (maximum sulfur 0.025%). Thus 75 a specific heat of stainless steel made to conform with

the nominal composition just outlined, had an analysis as follows:

TABLE III

	Percent
Chromium	16.24
Nickel	4.25
Manganese	2.21
Silicon	0.43
Carbon	0.123
Copper	0.9
Boron	0.14
Phosphorus	0.014
Molybdenum	2.20
Vanadium	0.38
Sulfur	0.010
Iron	Balance

A further example of the new alloy was a relatively large heat having the following composition, as analyzed:

TABLE IV

	Percent
Chromium	15.82
Nickel	4.48
Manganese	2.26
Silicon	0.58
Carbon	0.13
Copper	1.10
Boron	0.12
Phosphorus	0.011
Molybdenum	2.23
Vanadium	0.24
Sulfur	0.013
Iron	Balance

Metal from this heat was cold rolled, with annealing at 1950° F. It was subsequently re-annealed at 1700° F. (being the trigger anneal), and pieces were thereafter refrigerated at -100° F. for one hour and finally aged for six hours at 875° F. The resulting metal showed a tensile strength of 205,000 p.s.i., 0.2% offset yield strength of 185,000 p.s.i., and elongation (in 2 inches) of 7%.

In making the alloys, conventional procedures can be followed, i.e. as employed heretofore for the production of stainless steel alloys. That is to say, the melt may be produced in an electric furnace or other suitable equipment, with the alloying ingredients all there included, or alternatively by including most of such ingredients in the furnace, with ladle additions of special ingredients present in minor amounts. The form of adding the various elements may be such as is customary for incorporating these elements in other iron and steel compositions, for example as by the use of various ferro alloys where appropriate.

The produced metal may be cast in conventional ingot form, and the ingots thereupon reduced, for example by hot rolling or by combinations of hot rolling or forging, and cold rolling, to appropriate stock, viz. sheet, strip, bar, rod or the like. Where cold rolling is used, intermediate annealing may be effected at 1900° F. or thereabouts; with this anneal, which has been described hereinabove and which is called a solution anneal, a completely austenitic form is thus maintained, as best suited for mechanical deformation. The metal can be fabricated into the desired part, blank or other article at this time, and if it is to be hardened by refrigeration, it can thereafter be subjected to the trigger anneal at 1700° F. Alternatively, such fabrication can be postponed until after the trigger anneal. In either case, hardening is then effectuated by refrigeration and subsequent aging or tempering.

Described more generally, solution annealing (which is employed regardless of the selected mode of transformation to martensite) is effected by treating in the range of about 1850° F. to about 2000° F., preferably about 1900° F., and cooling rapidly. For ultimate refrigeration

hardening, the trigger anneal preferably comprises treating at about 1700° F. to 1800° F., and cooling rapidly. Annealing time is not critical for either step; for example, a time of ten minutes to one-half hour or so is suitable for the trigger anneal. If the metal has been trigger annealed prior to ultimate fabrication, it need not be so treated afterwards unless it was welded or non-uniformly deformed. Stated broadly, the range for martensite transformation at sub-zero temperatures is approximately -30° F. to -120° F.; the mechanism may in fact involve some beginning of transformation as the metal is cooled below freezing, with increase as the temperature is brought below 0° F. Particularly effective results, especially for assurance of complete transformation, are achieved by holding the metal in the range of -80° F. to -120° F., for a minimum of two hours, one preferred treatment being to hold it at -100° F. for eight hours.

If the alternative procedure of conversion to martensite at room or higher temperature is used, the solution-annealed metal is subjected to a special anneal at about 1400° F. On cooling, the transformation occurs as or before room temperature is reached. Thus in a broad sense, the range of trigger annealing may be said to extend from about 1350° F. to 1850° F. At the upper end of the range, the stability of austenite is only modified to the point where it will transform at very lower temperatures, whereas at the lower end of the range, the stability is greatly reduced (more carbon being removed from solution), whereby the transformation temperature or range is elevated, even to about 200° F. In general, distinctly better mechanical properties are obtained with the procedure which requires refrigeration for transformation.

Another alternative treatment involves cold working or other straining, for example as by so-called stretch forming. In general, this mode of treatment can only be relied upon for transformation effects if it is uniform throughout the piece of metal. Straining, i.e. as effected on metal that has previously been solution-annealed, can be effective to reduce the stability of austenite (e.g. as a substitute for trigger anneal at 1700° F.), or if of substantially greater magnitude, can bring about the transformation to martensite. For the first of these effects, a minimum of 10% to 15% elongation, throughout the work, is required; an alloy of the present type, so treated, will transform by refrigeration, without any trigger anneal. If there is substantially greater strain, as by more cold rolling or stretch forming, the transformation is brought about by such operation itself, i.e. without any low temperature treatment. For instance, reduction of 30% to 60% by cold rolling (preferably a reduction toward the upper end of such range), is generally needed in order to accomplish the martensite transformation by straining alone. It will be understood, of course, that the stated percentages of reduction by rolling will usually involve substantially lower percentages of actual elongation.

In all cases the metal is given the final aging or tempering treatment, preferably by holding in the range of about 800° F. to about 1100° F. for a minimum of one hour. The time may be considerably longer; indeed the treatment may be varied to adjust final properties. For instance, higher tempering temperatures, within the range, result in a property of higher elongation, but lower strength. Treatment at 850° F. for one hour or more is found to produce a good combination of strength and ductility.

By way of example, the following are instances of suitable forming, processing and fabricating operations for alloys of the present invention. In these examples, it may be assumed that the metal is first hot rolled (or otherwise formed, as by cold rolling) to strip, and then solution annealed at 1900° F. for ten minutes, and air

11

cooled; each procedure thus deals with solution-annealed strip.

Procedure A

- (1) Fabricate
- (2) Trigger anneal at 1700° F. for 10 minutes and air cool
- (3) Refrigerate at -100° F. for 8 hours
- (4) Temper at 850° F. for one hour and air cool

Procedure B

- (1) Cold roll to 30% reduction or more (e.g. 30% to 60%)
- (2) Temper at 850° F. for one hour
- (3) Fabricate (fabrication limited in this instance)

Procedure C

- (1) Fabricate
- (2) Anneal at 1400° F. for 2 hours and air cool
- (3) Temper at 850° F. for one hour and air cool

It will be seen that not only the alloy but also its mode of treatment, can be considerably varied to suit many different requirements or conditions of use. In all cases, there is provision for convenient working and fabrication, and for eventual treatment to reach desired, very high characteristics of strength, hardness and the like.

It is to be understood that the invention is not limited to the specific examples and operations herein described, but may be carried out in other ways without departure from its spirit.

We claim:

1. A stainless steel alloy consisting essentially of about: 12% to 20% chromium, 1% to 7% nickel, 0.5% to 5% manganese, 0.06% to 0.2% carbon, not more than 1% silicon, the total of nickel and manganese being not more than 7.5%; not more than 4% molybdenum, not more than 4% tungsten, not more than 1% vanadium, not more than 0.4% phosphorus, 0.75% to 1.5% copper, 0.04% to 0.3% boron, and the balance iron.

2. A stainless steel alloy consisting essentially of about: 12% to 20% chromium, 1% to 7% nickel, 0.5% to 5% manganese, 0.06% to 0.2% carbon, and up to 1% silicon, the total of nickel and manganese being not more than 7.5%, not more than 4% molybdenum, not more than 4% tungsten, not more than 1% vanadium, not more than 0.4% phosphorus, 0.5 to 3% copper, 0.01% to 0.7% boron, and the balance iron; the content of ingredients as aforesaid in the alloy characterizing it as one which is austenitic upon annealing at a temperature in the approximate range of 1850° F. to 2000° F., which

12

is transformable to martensite from said austenitic form and which in the martensitic form is adapted to be improved in mechanical property by treatment at a temperature in the approximate range of 800° F. to 1100° F.

5 3. A stainless steel alloy as defined in claim 2, which contains not more than 1.5% tungsten, not more than 0.4% vanadium, and 0.04% to 0.3% boron.

4. A stainless steel alloy consisting essentially of about: 14.5% to 17.5% chromium, 3% to 5.5% nickel, 2% to 10 4% manganese, 0.10% to 0.14% carbon, and up to 0.7% silicon, the total of nickel and manganese being not more than 7.5%; 1.5% to 3.5% molybdenum, not more than 1.5% tungsten, not more than 0.4% vanadium, not more than 0.3% phosphorus, 0.75% to 1.5% copper, 0.01% to 0.3% boron, and the balance iron.

15 5. A stainless steel alloy consisting essentially of about: 14.5% to 17.5% chromium, 3% to 5.5% nickel, 2% to 4% manganese, 0.10% to 0.14% carbon, and up to 0.7% silicon, the total of nickel and manganese being not more than 7.5%; 1.5% to 3.5% molybdenum, not more than 0.4% vanadium, 0.75% to 1.5% copper, 0.02% to 0.3% boron, and the balance iron.

20 6. A stainless steel alloy consisting essentially of about: 15% to 17% chromium, 4% to 6% nickel, 2% to 2.5% manganese, 0.1% to 0.15% carbon, 0.3% to 1% silicon, the total of nickel and manganese being not more than 7.5%, 2% to 3% molybdenum, not more than 0.4% vanadium, 0.5% to 1.5% copper, 0.02% to 0.2% boron, and the balance iron; the content of ingredients as aforesaid in the alloy characterizing it as one which is austenitic upon annealing at a temperature in the approximate range of 800° F. to 1100° F.
